DESIGN FOR AN OUTBOARD MOTOR TANK

Clarence Karstadt, Chicago, Ill., assignor to Sears, Roebuck and Co., Chicago, Ill., a corporation of New York

Application October 20, 1938, Serial No. 80,573

Term of patent 7 years

To all whom it may concern:

Be it known that I, Clarence Karstadt, a citizen of the United States, residing in Chicago, in the county of Cook and State of Illinois, have invented a new, original, and ornamental Design for an Outboard Motor Tank, of which the following is a specification, reference being had to the accompanying drawing, forming a part thereof.

Fig. 1 is a plan view of an outboard motor tank embodying my new design.

Fig. 2 is a side elevation of the same.

Figs. 3 and 4 are front and rear elevations of the same.

I claim:

The ornamental design for an outboard motor tank, substantially as shown.

CLARENCE KARSTADT.
